(57) **CLAIM**

The ornamental design for a deck attachment bracket, as shown and described.

DESCRIPTION

FIG. 1 is an oblique view of the deck attachment bracket; FIG. 2 is a left side elevation view thereof, the right side elevation view being a mirror image of the left side elevation view;

FIG. 3 is a front elevation view thereof;

FIG. 4 is a rear elevation view thereof;

FIG. 5 is a top plan view thereof;

FIG. 6 is a bottom plan thereof; and,

FIG. 7 is an oblique view of the deck attachment bracket in an example environment.

The dashed line showing of structural lines is included for the purpose of illustrating non-claimed subject matter and forms no part of the claimed design.
